UNITED STATES PATENT OFFICE

156,373

AUTOMOBILE WINDSHIELD SHADE

Albert R. Ross, Chicago, Ill., assignor to Dieterich Products Corporation, Oak Park, Ill., a corporation of Illinois

Application January 12, 1948, Serial No. 143,670

Term of patent 3½ years

(Cl. D14—6)

To all whom it may concern:

Be it known that I, Albert R. Ross, a citizen of the United States, residing at Chicago, in the county of Cook and State of Illinois, have invented a new, original, and ornamental Design for an Automobile Windshield Shade, of which the following is a specification, reference being had to the accompanying drawing, forming a part thereof.

In the drawing:

Figure 1 is a side elevational view of an automobile windshield shade showing my new design;

Figure 2 is a top plan view; and

Figure 3 is a slightly enlarged fragmentary front view of the right-hand bracket.

The dotted line showing is for illustrative purposes only.

I claim:

The ornamental design for an automobile windshield shade, substantially as shown and described.

ALBERT R. ROSS.
